1730, 1731, 1732, 1733, 1734, 1735, 1736, 1737, 1738, 1731, 1740, 1741, 1742, 1743, 1744, 1745, 1746, 1747, 1748, 1741, 1750, 1751, 1752, 1753, 1754, 1755, 1756, 1757, 1758, 1751, 1760, 1761, 1762, 1763, 1764, 1765, 1766, 1767, 1768, 1769, 1761, 1770, 1771, 1772, 1773, 1774, 1775, 1776, 1777, 1778, 1771, 1780, 1781, 1782, 1783, 1784, 1785, 1786, 1787, 1788, 1781, 1790, 1791, 1792, 1793, 1794, 1795, 1796, 1797, 1798, 1791, 1800, 1801, 1802, 1803, 1804, 1805, 1806, 1807, 1808, 1801, 1810, 1811, 1812, 1813, 1814, 1815, 1816, 1817, 1818, 1811, 1820, 1821, 1822, 1823, 1824, 1825, 1826, 1827, 1828, 1821, 1830, 1831, 1832, 1833, 1834, 1835, 1836, 1837, 1838, 1831, 1840, 1841, 1842, 1843, 1844, 1845, 1846, 1847, 1848, 1841, 1850, 1851, 1852, 1853, 1854, 1855, 1856, 1857, 1858, 1851, 1860, 1861, 1862, 1863, 1864, 1865, 1866, 1867, 1868, 1869, 1861, 1870, 1871, 1872, 1873, 1874, 1875, 1876, 1877, 1878, 1871, 1880, 1881, 1882, 1883, 1884, 1885, 1886, 1887, 1888, 1881, 1890, 1891, 1892, 1893, 1894, 1895, 1896, 1897, 1898, 1891, 1900, 1901, 1902, 1903, 1904, 1905, 1906, 1907, 1908, 1901, 1910, 1911, 1912, 1913, 1914, 1915, 1916, 1917, 1918, 1911, 1920, 1921, 1922, 1923, 1924, 1925, 1926, 1927, 1928, 1921, 1930, 1931, 1932, 1933, 1934, 1935, 1936, 1937, 1938, 1931, 1940, 1941, 1942, 1943, 1944, 1945, 1946, 1947, 1948, 1941, 1950, 1951, 1952, 1953, 1954, 1955, 1956, 1957, 1958, 1951, 1960, 1961, 1962, 1963, 1964, 1965, 1966, 1967, 1968, 1969, 1961, 1970, 1971, 1972, 1973, 1974, 1975, 1976, 1977, 1978, 1971, 1980, 1981, 1982, 1983, 1984, 1985, 1986, 1987, 1988, 1981, 1990, 1991, 1992, 1993, 1994, 1995, 1996, 1997, 1998, 1991, 2000, 2001, 2002, 2003, 2004, 2005, 2006, 2007, 2008, 2001, 2010, 2011, 2012, 2013, 2014, 2015, 2016, 2017, 2018, 2011, 2020, 2021, 2022, 2023, 2024, 2025, 2026, 2027, 2028, 2021, 2030, 2031, 2032, 2033, 2034, 2035, 2036, 2037, 2038, 2031, 2040, 2041, 2042, 2043, 2044, 2045, 2046, 2047

fillers and along the top at 27, can be performed from the exterior of the sills. The sills can be manipulated so that all welding is done vertically which is the most advantageous position for proper welding. The strikers are usually welded at 27 to the sills, to obtain firm connections.

In case of failure of a striker or center filler, due to wrecks or derailments, the striker and center filler castings can be removed by burning around the slots to remove the weld metal. New castings can be applied in the same manner as the original applications.

In actual practice, it will be noted that the slots in the castings are made generally 1" wide and 5" long, and in the sills, 1 1/4" wide and 5 1/2" long. This allows 3/8" overlap of the castings on the sills all around the slots for the application of 3/8" fillet welds. The welded construction shown will save approximately 200 pounds weight per car over the usual riveted construction. This saving in weight, together with the ease of application, provides an economical center sill construction.

The advantages of my improvements may be summarized, as follows:

1. Reduces weight. Approximately 200 pounds per car.

2. The welds are all made from the outside of the sills. This facilitates welding and inspection of welds.

3. A one piece steel casting is used for the striker and one for the center filler which requires the minimum of manual welding to attach them to the sills.

4. The one piece cast steel strikers and center fillers are economical to produce and the center filler can be hot die pressed to very close tolerances.

5. The castings act as spacers for the two Z sections which form the sills.

6. The castings can be removed by burning out the weld metal around the slots, leaving the slots in the sills approximately the same size as the original punching. New castings can be applied in the original manner.

From the foregoing, it is believed the construction of my draft attachments and the advantages thereof may be readily understood, and I am aware that changes may be made in the details disclosed, without departing from the spirit of the invention, as expressed in the following claims.

What I claim and desire to secure by Letters Patent is:

1. In a draft attachment for a railway vehicle, two substantially Z-shaped center sills each having a top wall arranged with a free edge thereof adjacent each other and welded therealong forming an inverted U-shaped member having spaced substantially vertical side walls and a single top wall, said side walls having a plurality of elongated slots therein disposed horizontally and in horizontal and vertical alignment, said top wall having slots therein aligned lengthwise of said member, a striker extending into said member having a top portion in flat engagement with an under surface of said top wall, said striker having slots therein of smaller dimensions than the slots in the top wall, each registering respectively with a slot in said top wall, welded metal along the boundaries of the slots in said top wall and around the slots in the top portion of the striker joining the striker to said top wall, substantially straight side surfaces on said

striker in flat engagement with inner surfaces of the respective side walls of said member, said striker having slots therein of smaller cross sectional dimensions than the slots in said side walls

5 each registering respectively with a slot in the side walls, welded metal along the boundaries of the slots in said side walls and around the slots in the sides of the striker joining the striker to the respective side walls of said member, a center 10 filler including webs having substantially straight side surfaces in flat engagement with corresponding inner surfaces of said side walls, said webs having slots therein of smaller dimensions than the slots in said side walls each registering respectively with a slot in said side walls, welded metal along the boundaries of the slots in said webs joining the center filler to said side walls, a flat surface at the top of the center filler in 15 engagement with an under surface of said top wall, said center filler having slots in the top thereof of smaller dimensions than the slots in said top wall each registering respectively with a slot in said top wall, and welded metal along 20 the boundaries of the last-mentioned slots and around the boundaries of the slots in the top of center filler joining the center filler to said top wall.

2. In a draft attachment for a railway vehicle, 30 a center sill structure of inverted U-shape having spaced substantially vertical side walls and a top wall, said side walls and said top wall having a plurality of slots therein, a striker extending into said sill structure having a top portion in flat engagement with an under surface of said top wall, an upper portion of said striker having slots therein of smaller dimensions than the slots in said top wall each registering respectively with a slot in said top wall, welded 35 metal along the boundaries of the slots in said top wall and around the slots in the upper portion of the striker joining the striker to said top wall, side surfaces on said striker in engagement with inner surfaces of the respective side walls 40 of said sill structure, said striker having slots therein of smaller cross sectional dimensions than the slots in said side walls each registering respectively with a slot in the side walls, welded metal along the boundaries of the slots in said side walls and around the slots in the sides of the striker joining the striker to the respective side walls of said sill structure, a center filler 45 having side surfaces in flat engagement with corresponding inner surfaces of said side walls of said sill structure, said center filler having slots therein of smaller dimensions than the slots in said side walls each registering respectively with a slot in said side walls, welded metal along the boundaries of the slots in said side walls and around the slots in the sides of the center filler joining the center filler to said side walls, a portion at the top of the center filler in engagement with an under surface of said top wall, said center filler having slots in the top thereof of smaller dimensions than the slots in said top wall each registering respectively with a slot in said top wall, and welded metal along the boundaries of the last-mentioned slots and around the boundaries of the slots in the top of center filler joining the center filler to said top wall.

3. In a draft structure for a railway vehicle, 55 two substantially Z-shaped center sills each having a top wall arranged with its free edge adjacent each other and welded therealong forming an inverted U-shaped sill structure having

spaced substantially vertical side walls and a top wall, said top and side walls having a plurality of slots, a striker extending into said sill structure having a top portion in engagement with an under surface of said top wall, an upper portion of said striker having slots therein of smaller dimensions than the slots in the top wall each registering respectively with a slot in said top wall, welded metal joining boundary edges of the slots in said top wall with top faces of the striker around the slots in said upper portion of the striker connecting the striker to said top wall, side surfaces on said striker in engagement with inner surfaces of the respective side walls of said sill structure, said striker having slots therein of smaller cross sectional dimensions than the slots in said side walls each registering respectively with a slot in said side walls, welded metal joining boundary edges of the slots in said side walls with outer side faces of the striker around the slots, a center filler including webs having outer side surfaces in engagement with corresponding inner surfaces of said side walls, said webs having slots therein of smaller dimensions than the slots in the side walls each registering respectively with a slot in said side walls, welded metal joining boundary edges of the slots in said side walls with outer side faces of the center filler around the slots in said webs connecting the center filler to side walls, top portions of the center filler engaging an under surface of said top wall, said top portions of the center filler having slots therein of smaller dimensions than the slots in said top wall each registering respectively with a slot in said top wall, and welded metal joining boundary edges of the slots in said top wall with upper face portions of the center filler around the slots in the top portions of center filler connecting the center filler to said top wall.

4. In a draft attachment for a railway vehicle, a center sill structure of inverted U-shape having spaced substantially vertical side walls and a top wall, said side walls and said top wall each having a plurality of slots therein, a striker extending into said sill structure having a top portion in engagement with an under surface of said top wall, an upper portion of said striker having slots therein of smaller dimensions than the slots in said top wall each registering respectively with a slot in said top wall, welded metal along the boundaries of the slots in said top wall and around the slots in the upper portion of the striker joining the striker to said top wall, side surfaces on said striker in engage-

ment with inner surfaces of the respective side walls of said sill structure, the sides of said striker having slots therein of smaller cross sectional dimensions than the slots in said side walls each registering respectively with a slot in the side walls, and welded metal along the boundaries of the slots in said side walls and around the slots in the sides of the striker joining the striker to the respective side walls of said sill structure.

5. In a draft structure for a railway vehicle, a center sill structure of substantially inverted U-shape having spaced substantially vertical side walls and a top wall, said side walls and said top wall each having a plurality of slots therein, a center filler including webs having outer side surfaces in engagement with corresponding inner surfaces of said side walls, said webs having slots therein of smaller dimensions than the slots in the side walls each registering respectively with a slot in said side walls, welded metal joining boundary edges of the slots in said side walls with outer side faces of the center filler around the slots in said webs connecting the center filler to side walls, top portions of the center filler engaging an under surface of said top wall, said top portions of the center filler having slots therein of smaller dimensions than the slots in said top wall each registering respectively with a slot in said top wall, and welded metal joining boundary edges of the slots in said top wall with upper face portions of the center filler around the slots in the top portions of center filler connecting the center filler to said top wall.

HARRY HAMILTON WOLFE.
